COMBINED ROOM DIVIDER AND CLOSABLE BAR

Maurice L. Lorge, 12167 69th Ave.,
Seminole, Fla. 33540

Filed June 29, 1973, Ser. No. 374,938

Term of patent 14 years

Int. Cl. D6—04

U.S. Cl. D6—144

FIG. 1 is a front perspective view of a combined room divider and closable bar showing my new design.

FIG. 2 is a view in side elevation taken from the right of FIG. 1 and on a reduced scale.

FIG. 3 is a left front elevational view thereof.

FIG. 4 is a top plan view thereof in open position.

FIG. 5 is a bottom plan view thereof in open position.

FIG. 6 is a first rear elevational view thereof in open position.

FIG. 7 is a second rear elevational view thereof in open position.

FIG. 8 is a top plan view thereof in closed position.

FIG. 9 is a front elevational view thereof in closed position.

FIG. 10 is a rear elevational view thereof in closed position.

I claim:

The ornamental design for a combined room divider and closable bar, as shown.
